MACHINE GUN AIR COOLING MEANS

Val A. Browning, Ogden, Utah, assignor to J. M.
& M. S. Browning Company, Ogden, Utah, a
corporation of Utah

Application October 29, 1940, Serial No. 363,262

6 Claims. (Cl. 89—14.1)

The present invention relates to machine guns and more particularly to an improved air cooled barrel structure for such guns.

The object of the present invention is to provide an air cooled barrel structure for machine guns of the recoil operated type having a readily interchangeable barrel structure such as that shown in the copending application of the same inventor Serial Number 363,263 filed on even date herewith. Heretofore machine guns of the recoil operated type have used water cooling because of the impossibility of readily interchanging the barrel. The water cooling is undesirable because of the necessity of having a water supply, means for circulating the water, and means for preventing leakage of the water into the breech structure. By providing an interchangeable barrel such as that shown in the above-mentioned copending application, it is possible to use the air cooling means of the present invention, thereby eliminating the disadvantages heretofore inherent in the use of water cooling.

Although particularly intended for guns of the recoil operated type, the barrel structure here may also be used on guns of the non-recoil operated type. Previously many attempts have been made to satisfactorily air cool such guns, but all such means have had serious disadvantages. In some instances a sleeve of light metal having high heat conductivity has been placed over the barrel; the sleeve being substantially coextensive in length with the barrel and intended to conduct the heat away from same, whereby, due to the greater surface area of the sleeve, rapid radiation of the heat into the surrounding air would occur. The difficulty with such a structure is that it is impossible in practical manufacture to obtain an intimate heat contact between a sleeve of substantial length and a barrel of substantial length, and, as a result, rapid conduction of heat from the barrel to the sleeve does not occur. Another means has been to make the barrel of substantial mass between the points where greatest heat is generated and then score the mass to provide radiating fins such, for example, as is done in the Hotchkiss gun. This type of structure greatly increased the weight of the gun and, in addition, offered considerable manufacturing difficulties.

Another object of the present invention is to provide a barrel structure having air cooling means wherein the difficulties heretofore encountered are overcome, and this is accomplished by utilizing air cooling means comprising a plurality of relatively short abutting heat radiating

members fixed to the barrel and intimately contacting the barrel surface. The advantage of using such heat radiating members is that an intimate contact with the barrel can be obtained over relatively short areas, and as each member makes such intimate contact and is likewise in abutting relation to its adjacent member, the result is in effect a continuous sleeve substantially coextensive with the barrel and having intimate heat contact with it throughout its length.

Another object is to provide the barrel with heat radiating members having radial fins or flanges of considerable size whereby both the mass and the radiation surfaces are substantially increased. By increasing the mass, greater heat conductivity between the barrel and the air cooling means is obtained, and by increasing the radiation surfaces a greater dispersion of heat into the surrounding atmosphere results.

Another object is to provide air agitating means associated with and positioned between the fins or flanges of the heat radiating members and so mounted that upon operation of the gun a rapid relative movement between said members and the agitating means is accomplished, thus setting up violent agitation of the air around the barrel structure.

A still further object is to provide air cooling means which may be manufactured with great ease and facility which permit of ready assembly onto the barrel as well as ready interchangeability of the barrel when the gun is in use and wherein said means do not require any sacrifice in weight to accomplish the results desired.

Other objects will be in part obvious and in part pointed out more in detail hereinafter.

The invention accordingly consists in the features of construction, combination of elements, and arrangement of parts which will be exemplified in the construction hereafter set forth and the scope of the application of which will be indicated in the appended claims.

In the accompanying drawings:

Figure 1 discloses a barrel structure incorporating air cooling means showing one embodiment of the invention herein;

Fig. 2 is a sectional view of Fig. 1 to show details of construction;

Fig. 3 is a view taken on the line 3—3 of Fig. 2;

Fig. 4 is a view of the embodiment shown in Fig. 1, but utilizing different means for supporting the air agitating means;

Fig. 5 is a view showing another barrel structure having air cooling means showing another embodiment of the invention herein;

Fig. 6 is a plan view of Fig. 5; and Fig. 7 is a view taken on the line 7—7 of Fig. 6. Referring to the drawings, the gun shown for purposes of illustration includes a receiver or breech casing 10, a barrel support 11, and a barrel 12. When used on a gun of the recoil operated type, the barrel support 11 and barrel 12 may be of the type which are readily removable from the breech casing 10; the structure for accomplishing this being shown in the above-mentioned copending application to the same inventor. For purposes of simplicity, no further description of the breech mechanism or the means for readily interchanging barrel structures will be included herein except to point out that upon recoil the barrel moves rearwardly approximately five-eighths of an inch relative to the receiver 10 and the barrel support 11. In the embodiments shown in Figs. 1 to 4 inclusive, the barrel support is in the form of a tubular jacket, the jacket having at its forward end a piece or plug 15 which slidably accommodates the barrel. The wall of the jacket is provided with slots or openings through which air may be passed.

In accordance with the invention herein, air cooling is accomplished by mounting on the barrel 12 (see Figs. 1 to 3) a plurality of cylindrical abutting heat radiating members 14 made of any suitable light metal having a high heat conductivity, such as an aluminum alloy. Each member 14 comprises an elongated body portion 16 provided with a central bore 18 through which the barrel passes, and a radiating fin or flange 19 having a thickness equal to approximately half the length of the body portion 16 and a diameter approximately equal to the inside diameter of the barrel support jacket. With the members 14 so constructed, they are secured onto the barrel of the gun in any suitable way, such as by shrinking them thereon, and, when mounted in the manner shown, a substantial air space is provided between adjacent radiating flanges 19, whereby their front and rear surfaces 21 will serve to deflect air from this space as the barrel moves back and forward during the firing of the gun.

It will be noted that with the heat radiating members so constructed the total length of each is relatively short in comparison to the overall length of the gun barrel 12. Because of this, it is possible to obtain an intimate heat contact between the bore of each member and the short length of barrel it surrounds, and, inasmuch as the members 14 are in abutting relation thereon, there is provided in effect a continuous sleeve coextensive with and intimately contacting the length of barrel subjected to the highest heat. Because of this intimate contact, the heat is rapidly conducted from the barrel to the members 14, and the latter present a far larger radiating surface for air cooling because of the increase in diameter over the barrel 12. By the further inclusion of the radiating flanges or fins 19, a substantially greater mass of metal is provided, resulting in more rapid conductivity of heat from the barrel and further increasing the radiating surfaces for rapid dispersion of the heat.

In addition, the air cooling means further includes air agitating means comprising plates or impellers 20 interposed between the fins of the members 14 and adapted to cooperate therewith to set up a violent agitation of the air currents upon operation of the gun. To accomplish this,

each impeller means 20 comprises a relatively circular plate 22 of relatively light thin metal having an outside diameter substantially corresponding to that of the radiating fins 19 and a central opening 24 of such diameter that it loosely fits the body portion 16 of its cooperating member 14.

The impellers 20 are associated with or carried by the barrel support 11, whereby upon operation of the gun the radiating fins 19 will move rapidly towards and from the impellers 20 to produce a pumping or blowing action and create violent air currents about the barrel. Although the impellers may be secured in various ways, they are here shown mounted on a rod 32 having its forward end secured in the forward end piece 15 of the barrel support 11 and its rear end abutting the rear end piece of the barrel support. The rod 32 has cut therein spaced circumferential grooves 33 for receiving and holding oppositely disposed spring ears 25 formed on each impeller 20 (see Fig. 3). The ears 25 are formed by cutting a narrow radial slot 26 extending from the periphery of the impeller and then cutting slits 28 at right angles to the slot. The slot 26 is preferably narrower than the diameter of rod 32 in the grooves 33, whereby when the parts are assembled the ears will snap into place and hold the impellers against longitudinal movement on the rod.

As previously indicated, when the impellers 20 are so mounted in a gun of the recoil operated type, the radiating fins 19 will move relative thereto, resulting in a pumping or blowing action which will create a rapid circulation of the air in the areas between the adjacent fins, thus greatly increasing the air flow in and around the barrel structure and the radiation of heat therefrom. Moreover, as the impellers or agitating means 20 are of relatively light material and fixed only at one point, they will, due to the rapid firing of the gun, set up an extremely fast fluttering action which will further aid in the creation of air flows in and about the barrel structure.

In order to permit rapid assembly of the barrel structure, the impeller plates 20 are mounted on the barrel simultaneously with the members 14, and each member has cut therein a U-shaped notch 34 with which the slots 26 of the plates 20 may be aligned, and, when so assembled, the barrel structure may be inserted into jacket 11. The rod 32, having been secured to the front end piece 15, is then inserted through the impeller slots 26 and notches 34 until its rear end is seated against the rear closed end of the barrel support. With the rod so seated, the front end piece 15 will also be seated in the outer end of the jacket 11 and may be secured in any suitable manner, as by the screws 35.

Referring now to the embodiment illustrated in Fig. 4, it is generally similar to that shown in Figs. 1 to 3 except for the construction of the impeller or agitating means retaining rod 38. The rod 38 is provided at both ends with a counterbore 40 in which there is seated a spring 42. The bore 40 at the rear end of the rod 38 telescopes onto a pin 44 secured in the flange of the rearmost member 14 on the gun barrel, and the bore of the forward end of the rod 38 telescopes onto a pin 46 secured in the flange of the foremost member 14 on the barrel, thus suspending the rod between the pins 44 and 46. With this construction, upon operation of the gun the pins will move forwardly and backwardly simultaneously with the radiating fins 19 and will cause

compression of the springs 42, thus setting up a rapid simultaneous sliding movement of both the rod 38 and the impellers 20 carried thereby.

The foregoing construction further facilitates assembly in that the pins 44 and 46 may be secured into the members 14, whereupon the rod 38 may be mounted prior to the telescoping of the jacket over the barrel structure.

In the embodiment illustrated in Figs. 5 to 7, the barrel support 49 comprises a pair of laterally spaced, parallel side plates 50 having their forward ends secured to a front end piece 52 and their rear ends secured to rear end piece 53 attachable to the receiver 10. As in the first embodiment, there is provided on the barrel a plurality of abutting members 54, each member being of relatively short length in comparison to the overall length of the barrel. In this embodiment, each member 54 includes a rectangular body portion 56 positioned between side plates 50 and having a bore 58 through which the barrel passes. Here, however, the odd numbered members, counting from the forward end, are provided with laterally extending radiating flanges or fins 60, whereas the even numbered members have vertically extending radiating flanges or fins 66.

Referring initially to the radiating flanges or fins 60, they are of triangular cross section and lie outside of the side plates 50 and are connected to the body portions 56 by throats 62. As indicated, the apex of the triangle is at the top of the flange 60, thus providing opposite air deflecting surfaces 64 inclined toward one another and which, when moved back and forth, deflect the air currents upwardly.

On the other hand, the radiating flanges or fins 66 extend vertically from the body portions 56 and are of trapezoidal cross section and lie between the crossplates 50. As seen, the opposite faces of flanges 66 are upwardly and inwardly inclined toward one another and will, upon forward and rearward movement upon operation of the gun, deflect the air currents upwardly. As in the first embodiment, the provision of radiating flanges also substantially increases the mass of the members 54 and provides a larger area for conducting the heat away from the barrel as well as providing larger radiation surfaces.

In order to further agitate the air currents in and around the segments, there is also provided between the vertical radiating flanges 66 a plurality of baffles or plates 70 of relatively thin metal mounted in vertical slots 72 cut in the inner walls of the side plates 50. With this arrangement, upon operation of the gun the members 54 will move relative to the baffles 70 to produce a pumping or blowing action, causing a rapid agitation of the air in and about the vertical radiating flanges 66. Simultaneously, the lateral radiating flanges 60 deflect the air upwardly along the side plates 50 carrying away the heat of the side plates and creating an up-draft tending to draw the heated air from between the side plates.

The construction shown in Figs. 5 to 7 is also readily assembled as the members 54 may also be initially secured onto the barrel as by shrinking them thereon. Thereafter the side plates 50 may be located in the grooves formed between the lateral flanges 60 and the body portions 56, and the plates 50 then secured to the end pieces 52 and 53. Following this, the baffles 70 may be readily slid into position between the side plates 50.

From the foregoing it will be seen that in all of the embodiments of the invention illustrated herein substantially the entire area of the barrel which is subjected to high heat is enclosed within a sleeve consisting of a plurality of members, each member having a relatively short length in comparison to the overall length of the barrel. This short length assures an intimate contact with the short length of the barrel which passes therethrough, resulting in rapid heat conductivity therebetween. In addition, each member further carries radiating means which greatly increase both the mass of the member and the radiating surfaces thereof for rapid dissemination of heat. Likewise, in each embodiment there is provided means to cause a rapid agitation or violation of the air currents upon the firing of the gun, due to the relative movement between the radiating flanges fixed to the barrel and the impellers or baffles located therebetween.

It is also evident that the air cooling means could be used on guns of the non-recoil operated type. In like manner, the agitating means could be used in conjunction with other types of air cooling means and also on non-recoil operated types of guns. In such guns, because of the manner in which the agitating means are suspended, vibration from the gun would be sufficient to set up rapid movement thereof, whereby they will tend to displace the air and cause rapid circulation in and around the barrel structure.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. A machine gun barrel structure comprising a barrel, a plurality of longitudinally spaced apart heat radiating flanges fixed to the barrel and in intimate heat contact therewith, a plurality of air agitating plates interposed between said flanges, and means supporting said plates for movement relative to one another and relative to said flanges whereby when the gun is fired said plates are set in rapid motion to cause deflection of the air from the spaces between said flanges.

2. A machine gun barrel structure comprising a barrel, a plurality of longitudinally spaced apart heat radiating flanges fixed to the barrel and in intimate heat contact therewith, a plurality of air agitating plates interposed between said flanges, a member extending longitudinally of said barrel and with respect to which the barrel is movable when the gun is fired, and means resiliently connecting said plates to said member.

3. A machine gun barrel structure comprising a barrel, a plurality of heat radiating flanges spaced apart longitudinally of the barrel and encircling the same and in intimate heat contact therewith, a rod spaced from the barrel and extending longitudinally thereof, means supporting the rod, and a plurality of air agitating plates in-

terposed between said flanges and flexibly connected to said rod.

4. A machine gun barrel structure comprising a barrel, a plurality of heat radiating flanges spaced apart longitudinally of the barrel and encircling the same and in intimate heat contact therewith, a rod spaced from the barrel and extending longitudinally thereof, said rod having spaced apart circumferential grooves, means supporting the rod, and a plurality of air agitating plates surrounding the barrel and interposed between said flanges, each of said plates having a pair of opposed spring fingers engaging in a respective groove of said rod.

5. A machine gun barrel structure comprising a barrel support, a barrel supported thereby for longitudinal movement relative thereto, a plurality of heat radiating flanges spaced apart

longitudinally of the barrel and encircling the same and in intimate heat contact therewith, a rod carried by said support and extending longitudinally of said barrel, and a plurality of air agitating plates interposed between said flanges and connected to said rod.

6. A machine gun barrel structure comprising a barrel, a plurality of heat radiating flanges spaced apart longitudinally of the barrel and encircling the same and in intimate heat contact therewith, a rod extending longitudinally of said barrel, means carried by the front and rear radiating flanges supporting said rod for longitudinal movement, compression springs interposed between said supporting means and said rod, and a plurality of agitating plates interposed between said flanges and connected to said rod.

VAL A. BROWNING.
